UNITED STATES PATENT OFFICE

HENRY LEE ALSTADT, OF RECTOR, ARKANSAS

BANK-PROTECTING DEVICE

Application filed January 21, 1929. Serial No. 333,950.

This invention relates to protecting devices for use in banks, an object being to provide means which may be controlled by an employee or other authorized person to protect such person from the attack of a bandit or bandits, as well as to protect the funds of the bank.

Another object of the invention is the provision of means for preventing the escape of the bandit or bandits, the said means being controlled by the employee and actuated simultaneously with the protecting means above referred to, so that a single movement of the bank employee from any position behind the counter or cage will render the protecting and escape prevention means active.

With the above and other objects in view, the invention further includes the following novel features and details of construction, to be hereinafter more fully described, illustrated in the accompanying drawings and pointed out in the appended claims.

In the drawings:

Figure 1 is a sectional view illustrating the floor plan of a bank and the arrangement of the protecting device.

Figure 2 is a sectional view taken substantially on the line 2-2 of Figure 1.

Figure 3 is a like view on the line 3-3 of Figure 1.

Figure 4 is an elevation of one of the window protectors or screens.

Figure 5 is an enlarged section taken substantially on the line 5-5 of Figure 1.

Figure 6 is an enlarged horizontal section illustrating the bank entrance and doors.

Figure 7 is a similar view taken horizontally through the compartment which houses the door operating mechanism.

Figure 8 is a fragmentary vertical sectional view on the line 8-8 of Figure 7.

Figure 9 is an enlarged section taken substantially on the line 9-9 of Figure 3.

Figures 10 and 11 are enlarged fragmentary sections taken respectively on the lines 10-10 and 11-11 of Figure 7.

Figure 12 is a fragmentary section taken substantially on the line 12-12 of Figure 5.

Figure 13 is a fragmentary vertical sectional view on an enlarged scale illustrating the manner of holding the panels in elevated position.

Figure 14 is a similar view showing the holding means moved to panel releasing position.

Figure 15 is a plan view with the releasing bar in section.

Figure 16 is an elevation of the rotary switch gear.

Referring to the drawings in detail wherein like characters of reference denote corresponding parts, the reference character 15 indicates a banking room which may be of any suitable type and which is provided with an entrance door 16 and windows 17. The banking room is divided by means of a partition which includes a counter 18, and provides a space for the tellers and other employees. The bank may be provided with a vault 19 and an office 20, while tables 21 may be placed within the office and distributed behind the partition for the convenience of the employees.

Rising from the counter 18 and forming a part of the partition is a superstructure 22. This superstructure may comprise a section 23 formed of bullet-proof glass and provided with an opening 24. The superstructure may also include a grill 25 having an opening 26.

The opening 24 may be closed by a horizontally slideable panel or door 27 which is moved to closed position by means of springs 28, the latter being mounted upon rods 29. Extending from this door is a lug or projection 30 and arranged to engage this lug is a lug 31.

The lug 31 is carried at the upper end of a vertically movable rod 32 which is yieldingly forced downward by means of a spring 33. This rod is mounted for sliding movement through the counter 18 and through a guide 34 and its lower end engages a cam 35 which is fast upon a shaft 36 extending longitudinally beneath the counter. By reference to Figures 5 and 12 of the drawings it will be seen that when the shaft 36 is rotated, the cam 35 will lift

the rod 32 out of the path of the lug 30 and the door or closure 27 will be moved to close the opening 24 under the action of the springs 28.

5 The section 25 of the grill has its opening 26 protected by a barred closure 37 and this closure may be connected by means of conductors 38 in circuit with a source of current 39, a high tension coil 40 being included in the circuit so that the current passing through the barred closure 37 will be of relatively high voltage. Included in circuit with the high tension coil 40 by means of a conductor 41 is a normally open switch 42, 10 a conductor 43 connecting this switch with a common lead 44 from the source of current 39. A conductor 45 is provided to complete a circuit through the source of current and high tension coil when the switch 42 is closed. The operation of this switch will be later described. If desired, the grill may be in electrical contact with the barred closure 37 so that when the switch 42 is closed the entire grill may be 15 electrified.

The shaft 36 is operated by a motor 46 and this motor is connected in circuit with a plurality of switches 42 by means of a conductor 47 and the conductor 44, while 20 interposed in this circuit is a switch 48. This last mentioned switch is normally open and comprises a gear 49 which carries an arcuate contact 50. This contact is connected with the motor 46 by a conductor 51, 25 while the conductor 41 is connected with a spring contact 52 which wipes against the arcuate contact 50. The gear 49 is driven from a pinion 53 which is mounted upon the shaft 36. Thus when any of the switches 42 are closed, a circuit will be closed through the motor 46 so that the shaft 36 will be operated to raise the rod 32 as previously described, and in addition, close a circuit through the motor and through the grill closure 37 for a period determined by the 30 length of the contact 50.

The switches 42 are connected in parallel and each includes a stationary contact 54 and a movable contact 55. The contact 55 35 extends downward from a common operating bar 56 which is yieldingly held against downward movement by springs 57, so that the switches 42 will be normally open.

In order to protect employees behind the 40 grill 25, the invention provides horizontally disposed spaced panels 58. These panels are positioned above the grill and extend horizontally and have their opposite ends 45 movable in guide rails 59. These guide rails are provided with slots 60, 61 and 62 which receive the ends of the panels, and as shown in Figure 5 of the drawings, these slots are of different lengths, so that when the panels 50 move downward within the slots they will

be so placed as to provide a complete closure across the grill 25.

In order to hold the panels elevated, the latter are provided at their upper edges with shoulders 63. These shoulders are 55 adapted to be engaged by spaced hooks 64 which depend from a slide 65, the latter being mounted for horizontal sliding movement within grooved guides 66. This slide is provided with an opening 67 at one end 60 for the passage of a vertically movable rod 68 and the latter is provided with an inclined portion 69.

By reference to Figures 5, 13, 14 and 15 of the drawings it will be seen that when the rod 68 is moved upward, the slide 65 will be moved outward due to its inclined portion 69 and the hook 64 will be moved from the position shown in Figure 13 to the position shown in Figure 14 so that the panels will be released. The panels will then descend by gravity to the bottom of the 75 slots.

By reference to Figure 5 of the drawings it will be seen that a rod 68 is positioned at 80 each end of the panels and these rods extend downward through openings provided in the counter and through guides 67. The lower ends of the rods bear against cams 71 which are carried by the shaft 36 and by 85 a shaft 72. This last mentioned shaft is disposed at right angles to the shaft 36 so as to control the panels at the end of the counter. The rods 68 are provided with springs 73 which yieldingly resist upward 90 movement.

It will be apparent from the foregoing description and accompanying drawings that when one of the bars 56 is depressed, a circuit will be closed through the motor 46 and through the barred closure 37. Operation of the motor will release the closure 27 and will in addition release the panels 58 so that the closure 27 will close the opening 24 in the bullet-proof section of the 95 superstructure and the panels 58 will close the openings in the grill 25. Employees behind the counter will thus be protected, while the bullet-proof glass portion of the superstructure will afford a view of the 100 customer's side of the counter.

In addition, the windows 17 may be closed by metal grills or screens 74 and these grills or screens may be connected in circuit with the high tension coil 40 through the conductors 75. The window screens or grills may be suitably grounded as indicated at 105 76 so as to provide for a return of current.

The entrance 16 may be provided with a vestibule 77 and the outer end of this vestibule may be provided with swinging doors 78. The inner end of the vestibule is provided with swinging doors 79 which as shown in Figures 1 and 6 of the drawings are adapted to be swung in opposite direc- 110 115 120 125 130

tions. To provide for this, the vestibule at its inner end is provided with a post 80 from which extends tangentially disposed ribs 81 with which the doors 79 are adapted to engage. Normally, the post 80 which is rotatable, is positioned as shown in Figures 1 and 6 of the drawings so that one door will open outwardly and the other inwardly. Offset stops 82 are provided adjacent the post 80 so as to limit outward swinging movement of one door and inward swinging movement of the other door, whereby, when the post 80 is rotated in a clockwise direction in Figure 6 of the drawings, the ribs 81 will engage upon the side edges of the door opposite the stops 82 and hold the doors closed.

To accomplish the foregoing, the invention provides an operating mechanism which is housed within a compartment 83 positioned above the vestibule. The post 80 extends into this compartment and is provided with a rectangular extremity 84 which is engaged by the forked end 85 of a slide rod 86. A spring 87 acts to resist sliding movement of this rod in one direction and yieldingly holds the fork 85 engaged with the post.

Positioned within the compartment 83 is a bell crank lever 88. This lever is pivotally mounted as shown at 89 and has one of its arms extending through the housing of the compartment 83 and provided with a depending portion 90 to engage one of the doors 79. The other door 79 which is adapted to swing inward is engaged by a finger 90' which projects through an arcuate opening 91 provided in the housing of the compartment 83 so that this finger extends into the vestibule to engage the door 79. The finger 90' is carried by an arm 92 which is pivotally mounted within the compartment 83 as shown at 93, and when this arm is moved to the left in Figure 7 of the drawings, the inwardly swinging door 79 will be closed against its stop 82 and when the bell crank lever 88 is swung inward, the outwardly swinging door 79 will be moved against its stop 82.

In order to effect this movement, the bell crank lever 88 and arm 92 are connected to an evener 94 by means of flexible connections 95, the latter passing around guide pulleys 96 and being provided with extensible sections 97 to compensate for difference in movement. The evener 94 is guided upon the rods 98 and is yieldingly held against movement in one direction by springs 99. A cable 100 is connected to the evener and passes around guide pulleys 101 and is adapted to be wound upon a drum 102 which is mounted upon the shaft 72. Thus, when the motor 46 is energized to rotate the shaft 36, the shaft 72 will be likewise rotated to exert a pull upon the cable 100 and move the

doors 79 to closed position as previously described.

The slide bar 86 has connected thereto one end of a flexible member 103 which passes around a guide pulley carried by the evener 94 and has its opposite end connected to an arm 104 which is rigid with the post 80. The flexible member 103 is sufficiently slack to permit the doors 79 to reach a closed position before the slide bar 86 is disengaged from the post. As soon as disengagement occurs however the flexible member 103 will swing the arm 104 ninety degrees and position the ribs 81 upon the opposite edges of the door 79 as previously mentioned. A spring 105 returns the ribs to the position shown in Figure 6 when tension on the cable 100 is relieved, a stop 106 limiting movement of the arm 104 in one direction.

As rotation of the shaft 72 is controlled by the operation of the motor 46, the doors 79 will be closed simultaneously with the operation of the protecting device, so that persons upon the customer's side of the counter will be prevented from leaving through the doors, while the window 17 will be protected by the high tension current passing through the screens 74.

The invention is susceptible of various changes in its form, proportions and minor details of construction and the right is herein reserved to make such changes as properly fall within the scope of the appended claims.

Having described the invention what is claimed is: —

Combination with a door frame, and single doors hingedly mounted at the opposite sides of the frame one to swing inwardly and the other outwardly, a fixed stop arranged in the path of swinging movement of each door to prevent swinging thereof in the direction opposite to that intended, a post mounted for rotation upright midway between the opposite sides of the door frame, longitudinally extending ribs extending tangentially from the post at the opposite sides thereof to engage the free edges of the respective doors, at the sides thereof opposite the sides which engage the fixed stops, when the doors are closed, means operable to close said doors, and means operating automatically to rotate the post to effect engagement of the ribs thereon with the respective doors upon completion of the closing movement of the doors.

In testimony whereof I affix my signature.
HENRY LEE ALSTADT.
